(57) **CLAIM**

The ornamental design for a detecting device for nucleic acid, as shown and described.

DESCRIPTION

FIG. 1 is a top, front, left perspective view of the detecting device for nucleic acid, showing in a closed configuration, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear, right perspective view thereof, and;

FIG. 9 is a top, front, left perspective view of the detecting device for nucleic acid of FIG. 1, shown in an open configuration for clarity of disclosure.

In the drawings, the equal-length broken lines depict portions of the detecting device for nucleic acid that form no part of the claim design.
